(57) **CLAIM**

The ornamental design for a cap for writing instrument, as shown and described.

DESCRIPTION

FIG. 1 is a front elevational view of a cap for writing instrument according to the present invention;

FIG. 2 is a left side elevational view of the cap for writing instrument of FIG. 1, the right side view being a mirror image of the left side view;

FIG. 3 is a rear elevational view of the cap for writing instrument of FIG. 1,

FIG. 4 is a top plan view of the cap for writing instrument of FIG. 1;

FIG. 5 is a bottom plan view of the cap for writing instrument of FIG. 1; and,

FIG. 6 is a front perspective view of the cap for writing instrument of FIG. 1.
